BEVERAGE TRAY

Aaron G. Myers, Fort Worth, Tex., assignor to
D. L. Harlow, Tulsa, Okla.

Application July 28, 1958, Serial No. 51,950

Term of patent 14 years

(Cl. D44—10)

Figure 1 is a perspective illustration of a beverage tray formed in accordance with my new design;

I claim:

The ornamental design for a beverage tray, as shown.
